CHARLES ZARKIN, OF NEW YORK, N. Y.

ADJUSTABLE ROLLER BEARING.

Application filed May 2, 1924. Serial No. 710,515.

This invention relates to inking mechanism for printing presses and the like, and particularly to means whereby the spindle of the ink roller may be adjusted so as to work at the right distance relative to the co-acting plate cylinder and also whereby it may be maintained in the adjusted operative position.

On account of the fact that where the plate cylinder of a press is made in sections which are spaced in a longitudinal direction from each other, the weight of the ink roller is apt to press the thin printing plate downwardly a sufficient distance to enter one of said spaces when opposite the ink roll consequently carrying the latter along with it, in which case the continued rapid rotation of the plate cylinder is apt to cause the ink roll to jump and be thrown out of the said space or recess and away from the printing plate which results in the uneven printing of the sheet of paper operated upon.

In order to obviate this difficulty I have devised a roller bearing to support the spindle of the ink roll which roller bearing may rest on the bearer of the plate cylinder and be adjusted so that there shall be a light face contact between the ink roll and printing plate carried by the plate cylinder, and also whereby the invention may be adapted to be interchangeably used in printing presses where the said parts are of somewhat different sizes.

Another object of the invention is to provide means whereby the rollers of my bearing as well as the spindle of the ink roll may be kept properly lubricated at all times.

Another object of the invention is to provide adjusting devices of such a character that the plane of the centres of the rollers and the axis of the spindle of the ink roll may be caused at will to lie at different distances apart by a simple manipulation of the spindles of the rollers.

Another object of the invention is to provide a bearing for the ink roll which will work with very little appreciable friction.

A still further object of the invention is to provide a device of the class described which shall be simple in construction, inexpensive to manufacture and efficient in operation.

With the above objects of the invention, and other objects and purposes which will be described below, in view, the invention

consists in the construction, arrangement, combination and operation of parts hereinbelow set forth.

In the drawings, illustrative of embodiments of the invention, which accompany and form a part of this specification—

Figure 1 represents a side view of an article constructed according to the invention; Figure 2 is a front elevation, partly in section, of the same; Figure 3 is a side elevation, partly in section, of another embodiment of the invention; Figure 4 is a front elevation, partly in section, of the latter; and Figure 5 is a partial front diagrammatic view of a press in which my invention is used.

In one embodiment of the invention my roller bearing, as illustrated in Figures 1 and 2, comprises two complemental members 1 and 2 each having an interior channel 3, recesses 8 for the rollers, orifices 4 for bolts; bores 5 for the spindles of the rollers, and oil passages 6 leading respectively to the channel 3 and to the roller spindles contained in the bores 5 to automatically lubricate the same. When the parts are assembled a bushing 7 is entered in the channel 3 the interior surface of which bushing being preferably spirally grooved as at 7' in order to form channels or passages for the oil.

The roller spindles 9 each carries an enlarged longitudinally disposed eccentric portion 9' the ends of the said spindles being squared at one extremity as at 9² for convenience of manipulation, the other ends of the same terminating in a threaded part 9³ adapted to be engaged with a nut 10.

My tubular rollers 11 are entered into the recesses 8 at the lower part of the body members and enclose the said eccentric portions 9' of the spindles, one end 9² of the latter extending outwardly from the bearing at one side thereof and the other extremity projecting from the other side of the bearing and being held to the same in operative position by the nuts 10.

My roller bearings are located adjacent to the ends of the ink roll spindle 13 on opposite sides of the press between the spindle supports and the ink roll and the bearings are then mounted on the bearers 12' of the plate cylinder 12, which bearers lie adjacent to the outer faces of the plate cylinder. By loosening the nuts 10 the ends 9² of the spindles 9 may be turned thus carrying the

eccentrics 9' around and thereby raising or lowering the rollers 11, whereby the plane of the centres of the rollers 11 and the axis of the ink roll spindle 13 may be caused to lie at different distances apart, the effect of which will be to raise and lower my roller bearing as a unit and thereby cause the ink roll to be so adjusted as to approach or recede from the plate cylinder at will. After the rollers 11 have been carefully adjusted to the proper operative relation so that the ink roll will be at its proper location relative to the plate cylinder, the nuts 10 may be screwed down tight thus holding the working parts of my roller bearings permanently in place, on account of the latter lying so close to the ink roll, and preventing any sagging of the ink roll at the centre thereof.

In the embodiment of the invention illustrated in Figures 3 and 4 the body of my roller bearing is also made of two complementary members 14 and 15, the member 14 being formed with a yoke or U-shaped recess 14² in which the central part of the member 15 fits, both members terminating in bifurcated or yoke-shape portions 14', 15', to hold the rollers 11 both members having the central channel 3 and bushing 7 as in the other embodiment. In this instance, however, the spindles for the rollers comprise plain bolts 16 formed with an orifice 16' at the smaller ends in which any desired holding device, as a pin, may be inserted.

The member 15 is made with an extension 15² having a threaded orifice in which a screw 17 may work. When the parts are assembled on the spindle of the ink roll as before, the relative position of the body members may be regulated by manipulating the screw 17, the end of which bears against the cross piece of the yoke 14, whereby the plane of the centres of the rollers and the axis of the ink roll spindle may be caused to lie at different distances apart thus raising or lowering the ink roll at will.

After the parts are once placed in the proper adjusted and operative position they may be permanently held there by the said screw 17 and the set screw 18 which bears against the bushing 7. This roller bearing may have oil ducts similar to those already described, the same being omitted in the

drawings of this embodiment for clearness of illustration.

I wish it to be understood that I do not desire to be limited to the particular use or the exact details of construction shown and described, for obvious modifications will occur to persons skilled in the art.

What I claim as my invention is:—

1. In a device of the class described, a body comprising two complementary members mounted on the spindle of an ink roll, rotatable bodies carried by the said members, each body member having a recess to overlie a rotatable body.

2. In a device of the class described, a plate cylinder, a bearer therefor, a roller bearing having a body portion mounted on the spindle of an ink roller and supported by said bearer, rollers carried by the said body, eccentrics mounted in the rollers, and means to vary the distance between the plane of the centres of the rollers and the axis of the said spindle by turning the shafts of the eccentrics for purposes of adjustment.

3. In a device of the class described, an ink roll spindle, two body members mounted on the spindle, said body members having interior channels and bushings to enclose the spindle and enlarged lower portions and rollers carried thereby, means to adjust the position of the rollers, the said body members also having means to rigidly hold the two members together after the adjustment of the rollers.

4. In a device of the class described, a plate cylinder, a bearer therefor, a roller bearing having a body portion mounted on the spindle of an ink roller and supported by said bearer, rollers carried by the said body, eccentrics mounted in the rollers, and means to vary the distance between the plane of the centres of the rollers and the axis of the said spindle by turning the shafts of the eccentrics for purposes of adjustment, and also means to hold the body in its adjusted position by locking the body and eccentrics together.

Signed at New York in the county of New York and State of New York this 22nd day of April A. D. 1924.

CHARLES ZARKIN.
